DESIGN FOR A FOLDER FOR BILLS, COINS, CARDS, OR THE LIKE

Sidney Hyman, New York, N. Y.

Application August 26, 1943, Serial No. 111,002

Term of patent 7 years

To all whom it may concern:

Be it known that I, Sidney Hyman, a citizen of the United States, residing at New York, in the county of New York and State of New York, have invented a new, original, and ornamental Design for a Folder for Bills, Coins, Cards, or the like, of which the following is a specification, reference being had to the accompanying drawing, forming a part thereof.

In the drawing:

Fig. 1 is a front perspective of a folder for bills,

coins, cards or the like, showing my new design.

Fig. 2 is a rear perspective of the same.

Fig. 3 is a similar view to Fig. 1 in partially open position.

Fig. 4 is a similar view to Fig. 3, showing the folder in fully open position.

I claim:

The ornamental design for a folder for bills, coins, cards or the like, as shown.

SIDNEY HYMAN.
